UNITED STATES PATENT OFFICE.

FRANK A. WEBB, OF BEVERLY, MASSACHUSETTS, ASSIGNOR OF FIVE-EIGHTHS TO RUFUS H. WOODBURY AND JOHN B. WEBB, OF SAME PLACE.

ELECTRIC-LIGHTING ATTACHMENT FOR GAS-BURNERS.

SPECIFICATION forming part of Letters Patent No. 544,634, dated August 13, 1895.

Application filed March 11, 1895. Serial No. 541,315. (No model.)

To all whom it may concern:

Be it known that I, FRANK A. WEBB, a citizen of the United States, and a resident of Beverly, in the county of Essex and State of Massachusetts, have invented new and useful Improvements in Electric-Lighting Attachments for Welsbach Gas-Burners, of which the following, taken in connection with the accompanying drawings, is a specification.

10 This invention relates to means for electrically lighting Welsbach or Bunsen gas-burners, and it is carried out as follows, reference being had to the accompanying drawings, wherein—

15 Figure 1 represents a front elevation of a Welsbach gas-burner provided with my electric-lighting device. Fig. 2 represents a longitudinal section of the same, partly shown in elevation. Fig. 3 represents a cross-section 20 on the line 3 3 in Fig. 1, and Fig. 4 represents a similar section showing the wire-netting of the burner removed.

Similar letters refer to similar parts wherever they occur in the different parts of the 25 drawings.

In the drawings, A represents the usual gas-pipe having air-inlets A' A', as is common in what is known as a "Welsbach incandescent gas-light," having the suspended incandescent mantle B, chimney C, and socket or chimney-support D, as is usual in this kind of light.

E is the burner-tip attached to the upper end of the gas-pipe A, and provided at its 35 upper end with a cup-shaped burner-cap e, over which is fitted the burner F, having its upper end made of wire gauze or netting f, as shown in the drawings.

F' F' are side perforations in the burner F, 40 as shown in Figs. 1 and 2, through which air is admitted to the burner.

Within the cap e are arranged a stationary and a movable electrode, as follows: G represents the stationary electrode, which is secured in an insulated manner to the cap e, and to said electrode is metallically connected the battery-wire g, as shown. H is a yielding electrode or sweeper adapted to be metallically brought in contact with the stationary 45 electrode G at the time the gas is turned on.

The electrode H is attached to or forms a part of a downwardly-projecting metallic rod h, connected in a suitable manner to the gas-cock so that the electrode H shall close and break contact with the stationary electrode G at the time the gas is turned on by the said gas-cock, and thus automatically ignite the gas and air compound by electric means when turning on the gas.

In the drawings, Figs. 1 and 2, I have shown the gas-cock I as provided with four ports i, adapted to close and open the gas-passages a a in the pipe A, as shown in Fig. 2. To the end of the gas-cock is secured a ratchet-wheel K, and on the stem of said gas-cock is loosely hung a spring-actuated lever L, to which is pivoted the pawl-lever M, having a pawl m, adapted to engage the ratchet or pawl-wheel K in turning on or off the gas, as is common in electric gas-lighting devices.

The lower end of the rod h is pivoted to the lever L, as shown in Figs. 1 and 2.

I wish to state that I do not confine myself to any particular mechanism for opening and closing the gas-supply or actuating the electrode H, as this may be done by other suitable mechanism without departing from the essence of my invention.

N is a cord or chain attached to the pawl-lever N for actuating the gas-cock, as is common in electric gas-lighting devices.

From the above it will be seen the yielding electrode H will sweep by the stationary insulated electrode G when the cord N is pulled in opening the cock to turn on the gas to the 85 burner, causing a spark to be produced between the electrodes, by which the gas is ignited within the burner F.

When the operator releases his hold on the pull-down N the lever L is automatically returned by the influence of its spring to its 90 normal position shown in Fig. 1, causing the electrode H to again sweep by the electrode G, by which a secondary spark is produced to light the gas in case the primary spark 95 should have failed to ignite the gas.

The electrodes are located out of the flame when at rest, as shown. By this arrangement I am enabled to light incandescent Welsbach burners by electricity, thus obviating the diffi- 100

culty of lighting such burners from the top or otherwise, as is now the case.

I have illustrated and described the sparking device arranged in the mixing-chamber, 5 consisting of a movable and a stationary electrode, as I deem this the best form of sparking device in practice; but I do not limit my invention to a sparking device consisting of a movable and a stationary electrode, as other known descriptions of sparking devices are equally within the scope of my invention.

Having thus fully described the nature, construction, and operation of my invention, 15 I wish to secure by Letters Patent and claim—

1. In combination with a Bunsen burner F having air inlets F' and the incandescent mantle B suspended above it, a stationary insulated electrode G and a movable yielding electrode H arranged within the mixing chamber of said burner, the latter electrode being connected for operation to a gas cock on the gas supply pipe substantially as and for the purpose set forth.
2. In combination with a Bunsen burner F having air inlets F' and the incandescent mantle B suspended above it, a stationary in-

sulated electrode G and a movable yielding electrode H arranged within the mixing chamber of said burner and adapted to break and close the circuit for the purpose of igniting the gas within the said burner below its mantle, substantially as specified.

3. In combination with a Bunsen gas burner having gas and air supplies and a mixing chamber connected to such supplies, a stationary insulated electrode and a movable yielding electrode both arranged within said mixing chamber, substantially as and for the purpose set forth.

4. In combination with a Bunsen gas burner having gas and air supplies and a mixing chamber connected to such supplies, of a sparking device arranged within such mixing chamber, substantially as and for the purpose set forth.

In testimony whereof I have signed my name to this specification, in the presence of two subscribing witnesses, on this 1st day of March, A. D. 1895.

FRANK A. WEBB
